UNITED STATES PATENT OFFICE.

FREDERIC W. HILLARD, OF TOTTENVILLE, NEW YORK.

TYPE-WRITING MACHINE.

1,027,050.

Specification of Letters Patent. Patented May 21, 1912.

Application filed January 31, 1910. Serial No. 541,195.

To all whom it may concern:

Be it known that I, FREDERIC W. HILLARD, of Tottenville, in the county of Richmond and State of New York, have invented a certain new and useful Invention in Type-Writing Machines, of which the following is a specification.

My invention relates to the carriage and platen shift mechanism of visible-writing typewriting machines, and has for its object to provide a simple, efficient and durable ball bearing or other antifriction rolling device, for supporting the platen carriage and automatically adjusting it to wear by the overhanging weight of the carriage, whether the machine be one provided with only one character, or more than one character per type bar; also to provide a simple, easily operated and reliable shifting mechanism for the platen carriage in a machine having two or more characters per type bar.

Figures 1 and 2 show a side elevation, partly in section, of my device for mounting the overhung carriage on self-adjusting interposed rolling devices or bearing balls, which form the sole support for the carriage; and the figures also show the carriage mounted on a vibrating shift frame to move to upper and lower case printing positions. Fig. 3 is a detail.

I do not deem further illustration necessary because the device is a species of the genus shown in my pending application Sr. No. 603,845; filed August 25th, 1896; also because the mechanism is so simple as to be readily understood without further illustration.

Figs. 1 and 2 differ from each other merely in that in Fig. 1 the platen is normally in its lowest position, the overhanging weight of the platen being greater than the force of the lifting spring; whereas in Fig. 2 the reverse is true, namely, the spring is stronger than the overhanging weight and normally lifts the platen to its highest position. Hence in Fig. 1 the lower case position is the lowest position of the platen, as there shown, while in Fig. 2 the lower case position is the highest position of the platen as shown in that figure. Otherwise the description of both figures is the same.

The reference characters refer to same parts on both figures and both figures show the normal lower case printing position.

The carriage 1 is of the kind known as

overhung, mounted at the rear on bearing balls 2 and provided at the front with platen 3. The method of mounting the carriage on the bearing balls or interposed rolling devices is novel and advantageous. The upper bearing comprises a downwardly facing race-way 4 on the carriage and an opposable upwardly facing race-way 5 in the shift frame 6. The race-ways 4 and 5 and two interposed balls 2 (one being shown) are all mounted in the same vertical plane. On the other hand the lower bearing is arranged in a horizontal plane, and consists of the rearwardly facing race-way or bearing surface 7 on the carriage and the opposable frontwardly facing race-way 8 in the shift frame, and the two interposed balls 2 (one being shown). Hence the race-ways 4, 5 and their balls are arranged in a plane at right angles to the plane of the race-ways 7 and 8 and their balls. I have shown the race-way 7 as a plane surface, but it may be V-shaped like the others if preferred.

I intend to employ two balls in the upper race-ways and two in the lower race-ways, as usual, with the customary separating cages, not shown, and limit pins, not shown, to prevent escape of the balls from their race-ways and to hold them a properly spaced distance apart. Also to make the shift frame 6 the same width as the lateral width of the carriage, so as to provide a snug, narrow machine in which the carriage, in its lateral movement, passes beyond each end of the shift frame, owing to its mounting on the interposed rolling devices which travel only one-half the distance that the carriage does in feeding.

The shift frame 6 is mounted on two adjustable pivot screws 9, one at each end of the shift frame, which are threaded into supports on the main frame 10, at each end of the shift frame. Preferably the pivot screws 9 have cylindrical pivot bearings that are inserted into sockets in the shift frame, as shown in Fig. 3 and a hardened ball 11 is inserted at the bottom of each of said sockets, forming an anti-friction device in taking up end play on the pivot bearings of the shift frame 6. Each pivot screw 9 is preferably provided with a lock nut 12, and the two pivot screws are separable and adjustable with respect to each other. The shifting movement may be effected by any well known mechanism. I have illustrated

it as shifted by shift key 13, key lever 14, connecting wire 15, bell crank 16 and downwardly projecting lug 17 on the shift frame.

Normally in Fig. 1, the carriage and platen are held down in the lower case printing position by the overbalancing weight of the platen, and register with lower case character "a," but the lifting spring 18, tends to lift the carriage into the upper case printing position where the platen will register with upper case character "b" on the type bar A outlined in dotted lines; and when the shift key 13 is depressed the spring 18 assists in the lifting movement. Normally the shift frame in Fig. 1 engages stop screw 19 and upon the depression of the shift key it is moved out of engagement with said screw 19 into engagement with stop screw 20. Screws 19 and 20 are adjustable and are preferably provided with lock nuts 21. Lifting spring 18 is shown as adjustable by means of threaded pin 22 and adjusting nut 23. In the shifting movement the race-ways and balls swing with the carriage and platen, the race-ways 4 and 5 and their balls swinging in one direction and race-ways 7 and 8 and their balls in the opposite direction.

Normally in Fig. 2 the carriage and platen are held up in the lower case printing position by lifting spring 18, which moves the upper end of the shift frame into contact with adjustable stop screw 20. When the shift key 13 is depressed the shift frame is rocked, moving the upper race-ways 4, 5 and their balls forwardly and the lower race-ways 7, 8 and their balls rearwardly, and swinging the platen downwardly into position for printing with the upper case type, this movement being limited by engagement of the shift frame with the adjustable, lower stop screw 19.

The impact point for the type at the front of the platen, and the axis of the platen and the axis of the shift frame are all set in the same horizontal plane, parallel to the plane of the lower race-ways 7, 8 and their balls, and at right angles to that of the upper race-ways 4, 5 and their balls. This arrangement gives a very rigid surface for the stroke of the type and particularly so on account of the frontward and backward facings of the lower race-ways, which thus offer direct resisting surface to the blow of the type bars. Gravity acts on the overhung platen carriage to constantly crowd together both the upper race-ways and the lower race-ways, which would not be true of the lower race-ways, were they upwardly and downwardly facing, instead of forwardly and rearwardly. Another advantage of my novel arrangement of race-ways is that they are yielding and can separate slightly to allow the balls to ride over dirt or gummed oil, etc., in the race-ways, which they could

not do were both the upper and lower race-ways set in the same vertical plane, as is common and well known. Still another advantage is that in my device the platen resists the blow of the type bar, as in the old style "blind" machines, by gravity, since if there is any looseness in the bearings, it is all taken up in the lower race-ways and interposed balls by the weight of the overhung platen, swinging downwardly upon the upper race-ways and their interposed balls as an axis and thus crowding the lower race-ways against their balls. Thus the blow of the type key comes against the platen rigid upon the lower bearings, and if there is any looseness at all it must be in the upper bearings, so that the blow of the type bar cannot move the platen unless it be to lift it against gravity by swinging it upwardly about the lower bearings as an axis. Hence, my cylinder is practically as rigid to the blow of the type bar as is the old style "blind" type of machine.

It will be observed that there is shown in the lower bearing, a V-shaped race-way in the shift frame and an opposing plane vertical surface for the balls on the carriage. This is an arrangement that automatically provides for wear and it is immaterial whether the V-shaped track be in the frame and the plane track on the carriage, or the reverse arrangement with the V-shaped track on the carriage and the plane one in the frame, the two being equivalents of each other. Two V-shaped ways may be employed if preferred in place of 7 and 8.

In order to prevent escape of the carriage from the shift frame, or escape of the balls, I provide a groove 24 in the lower edge of the carriage and a centrally located tongue 25 on the shift frame to enter said groove, there being a little play so that the carriage will be wholly supported on the balls 2 and not at all on the tongue and groove. A pivoted roller may be employed in place of the tongue 25 for anti-friction purposes, if preferred.

I have diagrammatically illustrated the type carrying end of a type bar A showing the upper b and lower a case characters inwardly inclined toward each other, as is necessary in connection with a vibratory carriage. The propelling power, escapement, ribbon movement, type bar system, key levers therefor, etc., are not illustrated, and it is not necessary to show them in order to illustrate my invention.

Having thus described my invention, what I claim and desire to secure by Letters Patent is:

1. In a front strike typewriter, the combination with a laterally-movable platen carriage, of two sets of rollers on which the carriage runs, a vertically arranged race bar for the rollers, connected to the carriage and

- having a downwardly facing race-way at the top and a rearwardly facing race-way at the bottom, an opposable vertically arranged shift frame for the rollers having an upwardly facing race-way at the top and a frontwardly facing race-way at the bottom, the upper race-ways and interposed rollers being arranged in a vertical plane, the lower ones arranged in a horizontal plane, and the pivotal axes of the shift frame and platen and the impact point at the front of the platen arranged in a horizontal plane at a level between the upper and lower race-ways.
2. In a front strike typewriter, the combination with a laterally movable platen carriage, of two non-opposing race-ways therein in the rear of the platen, a race bar having two race-ways, non-opposing with respect to each other but oppositely disposed with relation to the race-ways on the carriage, interposed rolling devices between said race-ways which entirely support the carriage and on which the carriage is adjusted to position by gravity, and a locking device arranged to prevent escape of the carriage and interposed rolling devices from the race-ways.
3. In a front strike typewriter, the combination with a laterally movable platen carriage, arranged and adapted to be held by gravity in one printing position, of two sets
- of rollers on which the carriage runs, a vertically arranged race-bar connected to the carriage and having a downwardly facing race-way at the top, and a rearwardly facing race-way at the bottom, an opposable vertically arranged shift frame having an upwardly facing race-way at the top and a frontwardly facing race-way at the bottom, said rollers being interposed in said race-ways, and a spring connecting the shift frame to the main frame and tending to lift the platen to another printing position.
4. In a front strike writing machine, the combination with the machine frame and a series of rearwardly striking types, of an oscillatory platen carriage, a race bar whereon said carriage runs, a pivotal support for the race bar, two race ways in the race bar on opposite sides of its pivotal support, corresponding race ways in the carriage and rolling devices in the race ways, and a spring connecting the race bar to the machine frame, and constantly tending to lift the carriage and to revolve one set of race ways in one direction and the other one in the opposite direction.

In testimony whereof, I affix my signature in the presence of two subscribing witnesses.

FREDERIC W. HILLARD.
